UNITED STATES PATENT OFFICE.

JOHN GICZEWSKI, OF WEST HAMMOND, ILLINOIS.

RAILWAY-CAR.

No. 904,256.

Specification of Letters Patent.

Patented Nov. 17, 1908.

Application filed November 16, 1907. Serial No. 402,378.

To all whom it may concern:

Be it known that I, JOHN GICZEWSKI, residing at West Hammond, in the county of Cook and State of Illinois, have invented 5 certain new and useful Improvements in Railway-Cars, of which the following is a full, clear, and exact description.

My invention relates to improvements in railway cars, and more particularly to improvements in railway cars of steel construction and to such end consists in certain novel features of construction and arrangement, a description of which will be found in the following specification and the essential features 15 of which will be more definitely set forth in the appended claims.

The invention is clearly illustrated in drawings accompanying this specification in which

20 Figure 1 is a side view of a portion of a railway car embodying my invention. Fig. 2 is a side view of a journal bearing plate. Fig. 3 is a detail horizontal section taken on line 3—3 Fig. 1. Fig. 4 is a detail vertical section taken on line 4—4, Fig. 1. Fig. 5 is 25 a vertical cross section taken on line 5—5, Fig. 1. Fig. 6 is a detail section taken on line 6—6, Fig. 5. Fig. 7 is a perspective view of a center brace or bracket that 30 forms part of the body bolster. Fig. 8 is a perspective view of a center brace or bracket of the truck bolster. Fig. 9 is a vertical cross section taken on line 9—9, Fig. 1. Fig. 10 is a detail cross section taken on line 35 10—10, Fig. 9. Fig. 11 is a detail cross section taken on line 11—11, Fig. 9. Fig. 12 is a perspective view of a corner piece for the truck bolster. Fig. 13 is a similar view of a fragment of one member of the truck 40 bolster. Fig. 14 is a similar view of a knee in said bolster. Fig. 15 is a perspective view 45 of a side plate. Fig. 16 is a similar view of the reverse side of the side plate. Fig. 17 is a horizontal section taken on line 17—17, Fig. 1. Fig. 18 is a perspective view of a 50 guide and reinforcing plate. Fig. 19 is an under plan view of a draw bar mechanism. Fig. 20 is an under plan view thereof with certain portions removed. Fig. 21 is a vertical section in line 21—21, Fig. 20. Fig. 22 is a perspective view of the draw bar. Fig. 23 is a similar view of a plate. Fig. 24 is a cross section taken on line 24—24, Fig. 21, and Fig. 25 is a perspective view of a 55 lower block.

Referring to the drawings 10, are the

longitudinal sills or stringers of a car body, 11, the truck and 12 the wheels, of a railway car built in accordance with my improved construction. The sills are preferably U-shaped in cross section and are connected together at points along their length by struts 13 which are preferably riveted to the sills.

Body bolsters 14, are secured upon the 65 under side of the sills at each end of the car and said body bolsters comprise upper and lower members 15, 16, and a center bracket or brace 17. The upper member 15 is preferably U-shaped in cross section, the side 70 flanges 18 of which project down from the flat horizontally extending top 19. The lower edges of the flanges 18, incline upwardly toward the ends of the bolster and are flanged outwardly as at 20, to provide 75 means whereby the lower members 16 may be secured to the upper member and also to further strengthen and reinforce the bolster. The flanges 20 and member 16 are preferably riveted together as shown, and the ends of 80 said lower member are bent up as at 21 to provide means for attachment of the lower member to the outer sills of the car body. This upward bend further closes up the end 85 of the hollow bolster and provides a finished appearance for the same.

The center bracket 17 (see Figs. 6, 7 and 9) preferably comprises a steel plate bent up to form a base portion 22, and vertical 90 sustaining plates 23, which have flanges 24 for attachment to the sides 18 of the body 95 bolster. A strut 25, extends between the vertical plates, 23, to further reinforce the bracket 17, and said strut 25 and the base 22 are centrally perforated to receive the king bolt 26.

The truck contains a truck bolster 27, (see Figs. 5, 6, 8, 9, and 11 to 14 inclusive) which in general comprises upper and lower members 28, 29, a center bracket 30 and certain 100 knees 31 and reinforcements 32 for the ends of the bolster. The upper member is U-shaped in cross section, the sides 33 extending down from the horizontal top 34, and being flanged outwardly for attachment to 105 the lower member 29. The lower edge of the truck bolster inclines upwardly from the center toward both ends and the lower member 29 is carried around the ends of the upper member, as at 35. A corner strut or 110 brace 36 is confined between the ends of the upper and lower members 28, 29, which strut

or brace preferably comprises a plate bent into a triangular shape to fit in the apex of the pointed ends of the bolster and the end of said struts are bent up and carried back 5 upon the upper member and between it and the end 35 of the lower member as shown, thereby giving much added strength to the ends of the bolster. The ends of the struts 32 are bent up to form the lower members 10 37 of the side bearings, the upper members of the side bearings being bent up of steel plates as shown at 37^a and riveted to the body bolster. The flanges are omitted from the ends of the sides 33 of the truck bolster, 15 as seen in Fig. 13, and said ends lie between vertical guide flanges 38 and a triangular shaped portion 39 of the knees 31. (See Figs. 1 and 15). Each of said knees, comprises an abutment member 40 for the 20 springs, the sides of which member are bent up to form the flanges 38, and the one end of which is bent up and then back toward the center of the bolster in a downwardly inclined direction parallel with the lower member 29 thereof, thus forming the triangular shaped portion 39, above referred to. The bolster rests upon said triangular portion and, which in turn rests upon the springs. The flanges 38 are bent back upon themselves 25 30 (see Fig. 14) to form grooves 41 upon the outer faces of said flanges, which grooves afford a sliding connection between the truck bolster and the side plates 42 of the truck. The knees and bolster are connected together 35 by bolts or rivets which pass through the flanges 38 of the knees and sides 33 of the bolster.

The center bracket 30 (see Fig. 8) of the truck bolster comprises a plate bent up to 40 form a top member 43, and sustaining members 44, which are flanged for connection with the sides of the bolster. The sustaining members 44, converge toward the center of the lower member 29, and are connected 45 by a strut 45 to further reinforce the bracket. The top member 43 and strut 45 are centrally perforated for the king bolt 26. Bearing plates 46, 47 are riveted to the body bolster and truck bolster respectively to form the 50 immediate connection between the relatively rotatable members.

The side plates 42 (see Figs. 1, 15 and 16), are provided with openings 48 for the reception of the journal boxes, 49, and with a 55 central opening 50 for the truck bolster and springs. The upper and lower edges of the plates 42 are formed with reinforcing flanges 51, and flanges 52, 53, are likewise provided at the upper and lower edges of 60 the openings 48, 50, respectively. The ends of the truck bolsters project through the openings 50, in the side plates and reinforcing plates 54, 55, are bolted upon the inner and outer faces of the plates 42, which reinforcing plates fit in to the grooves 41 of

the knees, and form guides upon which the truck bolsters move. The plates 55 are connected upon their lower ends by a flanged bar 56, and a cross bar 57 (see Figs. 5 and 9), is bolted to the flange of the bar 56, and 70 to the lower flange 53 of the opening 49. Said cross bar serves as a brace or connecting bar for the lower portions of the side plates 42.

The wheels 12 are journaled in journal 75 boxes 49 (see Figs. 1, 3 and 4) which are secured upon the side plates 42. Said boxes project through the openings 48 in the side plates and have flanges 59 that are riveted to the plates. The boxes practically fit the 80 openings 48 in the plates 42, and grooves 60, are provided in the sides of said boxes, to receive reinforcing plates 61. These plates are riveted to the side plates 42 and further secure the boxes upon the side plates. 85 Within the boxes are secured hooks 62 that are intended to hold waste or other oil saturated material, against the axles. Usually the waste falls to the bottom of the box and becomes useless. With this contrivance the 90 waste is maintained in active position at all times. The open ends of the boxes are preferably closed by hinged covers 63, that are kept in closed position by spring hooks 64.

It will be noticed that the flanges 52 of the 95 plates 42, form ledges or supports for the boxes, besides reinforcing and strengthening the plates at the journal box openings.

The coupler is seen at 65, (Figs. 19 to 24 inclusive). The draw-bar 66, has secured 100 to its rear or inner end, two yokes 67, 68, which are set at right angles to each other, to form an inclosure and abutment for the springs 69, 70. Between the springs is interposed a follower 71, which is substantially rectangular in form and fits between the longitudinal members of the yokes 67, 68. The follower is held stationary upon the car by means of tongues 72 that are stamped up from plates 73, 74. Above the plate 73 110 is a flanged draw-bar supporting plate 75 which is riveted to the sills 10 of the body.

The plates 73, 74, and two side plates 76 form a rectangular receptacle in which the draw bar is slidingly mounted and said side 115 plates 76 are flanged as shown and riveted to the plate 73. Supplemental reinforcing plates 77, 77^a, 77^b are provided below the plate 74, which supplemental plates are bolted to the plate 74, and lower flanges of 120 the plates 76 by means of bolts 78, and also to angle irons 79, by bolts 80. The angle irons are riveted to the middle sills 10 as shown.

The tongues 72, lie between the sides of 125 the yoke 68 as shown in Fig. 20 and engage the follower 71, to hold it against movement relative with the car. Blocks 81, 82, are interposed between the springs and draw bar, against which the springs bear. Any 130

pull upon the draw-bar will compress the spring 70 between the block 82 and follower 71. When the bar is pushed inward the spring 69 is compressed between the block 81 and follower 71.

5 I claim as new and desire to secure by Letters Patent:

1. In a steel car construction, a bolster comprising an inverted U-shaped upper member having flanges upon its lower edges, 10 said edges being inclined upwardly from the center, and a lower member riveted to said flanges, and having its ends bent up against the ends of the upper member.

15 2. In a steel car construction, a bolster comprising an inverted U-shaped upper member, having upwardly inclined lateral flanges upon its lower edge, a lower member riveted to said flanges, and an internal center bracket having an aperture for a kingbolt, 20 and arranged to extend between the upper and lower members.

25 3. In a steel car construction, a bolster comprising an inverted U-shaped upper member, having upwardly inclined lateral flanges upon its lower edge, a lower member riveted to said flanges, and a center bracket, comprising a flanged U-shaped portion secured to the sides of the upper member, and 30 a strut between the upright members of the brace.

35 4. In a steel car construction, a bolster comprising an inverted U-shaped upper member, having flanges upon its lower edges that incline upwardly, and a lower member secured to the flanges of the upper member, and having its ends bent around the ends of the upper member.

40 5. In a steel car construction, a bolster comprising an inverted U-shaped upper member, having flanges upon its lower edges that incline upwardly, a lower member secured to the flanges of the upper member, and having its ends bent around the ends of 45 the upper member, and corner reinforcements secured in the ends of the bolster between the upper and lower members.

6. In a steel car construction, a bolster comprising an inverted U-shaped upper member, having flanges upon its lower edges 50 that incline upwardly, a lower member secured to the flanges of the upper member, and having its ends bent around the ends of the upper member, and triangular shaped corner reinforcements fitting and seated between the meeting ends of the upper and lower members.

7. In a steel car construction, a truck bolster comprising an inverted U-shaped upper member, having upwardly inclined lower 60 edges that are flanged outwardly, a lower member secured upon the flanges of the upper member, and knees secured to said bolster having guide members for the side plates.

8. In a steel car construction, a truck comprising a body bolster, having guiding devices upon its ends, wheels, journal boxes, side plates having flanged openings for the body bolster and journal boxes, plates secured upon said side plates and sliding in 70 the guide devices upon the bolster, and supporting springs interposed between the side plates and bolster.

9. In a truck, the combination of side plates, having bolster openings, and flanges 75 upon their upper and lower edges and upon the upper and lower edges of the openings, a truck bolster, flanged guide plates secured upon the side plates and forming slidable connections between the side plates and 80 bolster, a cross brace extending through the openings in the side plates and secured to the lower flanges of said openings, and supporting springs between said cross brace and bolster.

85 10. In a truck, the combination of side plates, having flanged openings, journal boxes seated in said flanged openings, and flanged reinforcing plates secured upon the side plates, adjacent to the openings.

JOHN GICZEWSKI.
